FIG. 1.

FIG. 3.

FIG. 2.

INVENTOR:
JACOB A. MEHR,
By Lawrence R. Cohn
ATTORNEY.

UNITED STATES PATENT OFFICE

152,282

DESIGN FOR A COMBINED LAMP AND MAGNIFIER

Jacob A. Mehr, St. Louis, Mo.

Application September 13, 1947, Serial No. 141,383

Term of patent 14 years

(Cl. D48—20)

To all whom it may concern:

Be it known that I, Jacob A. Mehr, a citizen of the United States, residing at St. Louis and State of Missouri, have invented a new, original, and ornamental Design for a Combined Lamp and Magnifier, of which the following is a specification, reference being had to the accompanying drawing, forming a part thereof.

In the drawing:

Fig. 1 is a top plan view of a combined lamp and magnifier, showing my new design;

Fig. 2 is a bottom plan view thereof, and

Fig. 3 is a side elevational view thereof.

I claim:

The ornamental design for a combined lamp and magnifier, as shown.

JACOB A. MEHR.
